COOLING MEANS FOR ENGINES

William Robert Dittmar, Williamsport, Pa., assignor to The Aviation Corporation, New York, N. Y., a corporation of Delaware

Application January 22, 1945, Serial No. 574,014

14 Claims. (Cl. 123—173)

1

The invention relates to cooling cylinders of internal combustion engines.

One object of the invention is to provide cooling jackets for the engine cylinders which insure a flow or circulation of coolant around substantially all portions of the cylinder-barrel for efficiency in cooling.

Another object of the invention is to provide an improved cooling system for engine-cylinders in which the inlet and outlet connections for the coolant are connected solely to the cylinder head and coolant flows around substantially all portions of the cylinder-barrel and keeps the cylinder-barrel free from gas or air bubbles.

Another object of the invention is to provide an improved cooling system for cylinders of internal combustion engines which operates efficiently while the engine is being operated in different attitudes, as occurs in the use of engines in aircraft.

Other objects of the invention will appear from the detailed description.

The invention consists in the several novel features hereinafter set forth and more particularly defined by claims at the conclusions hereof.

In the drawings—

Fig. 1 is a longitudinal section through the cylinder and the cylinder-head of an internal combustion engine embodying the improved cooling system.

Fig. 1^a is a section taken on line 1^a—1^a of Fig. 2 on an enlarged scale.

Fig. 2 is a section taken on line 2—2 of Fig. 1.

Fig. 3 is a section taken on line 3—3 of Fig. 1.

Fig. 4 is a section taken on line 4—4 of Fig. 1.

Fig. 5 is a section taken on line 5—5 of Fig. 1.

The invention is exemplified in an internal combustion engine which comprises a crank case *a*, a cooled cylinder generally designated *b* which consists of a barrel in which the piston operates and a cooled cylinder-head *c* in which the inlet and exhaust valves are mounted, as well understood in the art.

The cylinder-head is provided with chambers *13* and *14*, through which coolant is circulated for cooling the head. Chamber *13* is communicatively connected to a pipe *e* and chamber *14* is communicatively connected to a pipe *f* for the circulation of liquid coolant, usually by a suitable pump, as well understood in the art. Chambers *13* and *14* extend around the walls of the valves (not shown) in the cylinder-head and a partition or wall *11* is formed in the head between said chambers. A port *12* is provided in wall *11* and permits the coolant to bleed from one of the chambers *13* and *14* to the other. The size of port *12* proportions the relative amount of coolant which flows through the head *c* or around the cylinder *b*. This construction exemplifies a cylinder-head with chambers and inlet and outlet connections for the coolant. The coolant from the

head is also circulated around the cylinder barrel, as hereinafter described.

The barrel of cylinder *b* is provided at its lower end with an annular shoulder *7*, which abuts against the crank-case *a*. An annular jacket-member or annulus *8* is shrunk or otherwise suitably secured on the cylinder barrel and against a shoulder *10* adjacent its upper end. The cylinder barrel is secured by any suitable means, between the crank-case and the cylinder head. A ring *9* of suitable heat-resisting material is compressed between the upper end of the annulus *8* and a ring *9a* which is confined in the cylinder head to form a seal for preventing the escape of gasses between the cylinder and the cylinder head. Annulus *8* is provided with an annular shoulder *10'* against which a ring *11* is compressed by the cylinder head to form a seal for preventing the escape of coolant between the coolant jacket and the cylinder-head.

20 The coolant-jacket comprises, besides the annulus *8*, a cylindrical jacket section *16*, the upper end of which is silver-soldered or otherwise suitably joined to the inner end of annulus *8*. A ring *17* is silver-soldered or otherwise suitably secured to the outer periphery of the lower end of jacket section *16* to close the lower end of the coolant-jacket.

25 The lower end of the jacket is spaced from the outer periphery of the cylinder-barrel. A ring *17* is shrunk around the shoulder *7* on the lower end of the cylinder-barrel to close the lower end of the coolant chamber. A sleeve or cylindrical partition *18* has its outer end shrunk or otherwise suitably secured to the outer periphery of the cylinder barrel and against an annular shoulder *10* adjacent the outer end of the cylinder barrel and extends downwardly in the coolant space between the jacket and the barrel and terminates above the shoulder *7* to divide a portion of the space between the jacket and the barrel into two annular passages through which the coolant will flow longitudinally in opposite directions and from one of the annular chambers to the other, through the annular space *20* below the lower end of sleeve *18*. An arcuate channel *22* is formed in the cylinder head around one side of the upper portion of annulus *8* and is communicatively connected to the coolant pipe *e* which also communicates with chamber *13* in the cylinder head. An arcuate channel *23*, transversely aligned with channel *22*, is formed in opposite side of the cylinder head and adjacent to the upper end of the annulus *8* and is communicatively connected to the pipe *f* which is also communicatively connected to the chamber *14* in the cylinder head. Direct communication between channels *22* and *23* is closed by the wall portions *24* and *25* of the cylinder-head which fit against the outer periphery of annulus *8* at diametrically opposite sides of the cylinder. An approximately semi-annular

series of ports 27 extend through the annulus 8 and communicatively connect arcuate channel 22 and the chamber between annulus 8 and sleeve 18 at one side and adjacent the upper portion of cylinder-barrel. The opposite side-portion of the annulus 8 fits arounds the inner periphery of the upper portion of annulus 18. An approximately semi-annular series of ports 26 extend through the annulus 8 and the sleeve 18 and communicatively connect the arcuate channel 23 and one side of the annular space between sleeve 18 and the cylinder barrel. The lower end of sleeve 18 is provided on its outer periphery with a series of lugs 30 which space the lower end of the sleeve from the jacket section 16. The spaces 31 between lugs 30 communicatively connect the annular space 20 and the annular space between sleeve 18 and jacket section 16. Chamber 13 in the cylinder-head is communicatively connected by a duct 40 indicated by dotted lines with an arcuate channel 22 which is communicatively connected to pipe e. Chamber 14 in the cylinder-head is communicatively connected by a duct 41 indicated by dotted lines with an arcuate channel 23 which is communicatively connected to pipe f.

The cylinder barrel is provided with a flange 28 which is cut away polygonally to provide chordal-shaped spaces 29 which communicatively connect the annular space 20 below sleeve 18 and the annular chamber between the cylinder barrel and sleeve 18. Adjacent its upper end and below ports 26 and 27 the cylinder barrel is provided with a flange 32 which is polygonally cut away to provide chordal-shaped ducts 33 which communicatively connect the upper and lower portions of the annular space between the cylinder-barrel and the sleeve 18.

The annular chamber between the cylinder-barrel and the sleeve 18 should be sufficiently thin to create a rapid flow of coolant therethrough to wipe all gas or air bubbles from the cylinder barrel, regardless of the attitude in which the cylinder is being used. The flange 32 and ducts 33 restrict the flow of coolant to provide an equal distribution of coolant to flow through the annular chamber between the cylinder barrel and sleeve 18 thereby preventing a short circuit flow of coolant to channel 22 and preventing air or gas from being trapped therein in some attitudes of the cylinder. A leak-port 35 in the sleeve 18 adjacent its upper end serves to bleed the annular chamber between the jacket and the sleeve to prevent air or gas from being trapped in the upper portion of said chamber.

The operation will be as follows: Assuming the pipe e is connected to the pressure side of the coolant pump and the pipe f to its inlet side, coolant will flow from pipe e to arcuate channel 22 in the cylinder-head e. Some of the coolant will flow from pipe e through chamber 13 and port 12 and partition 11 to the chamber 14 and then to the outlet pipe f for cooling the cylinder head. The coolant will flow downwardly through substantially all portions of the annular chamber between sleeve 18 and the jacket, then through the spaces 31 between the lugs 30 on the inner end of the sleeve into the chamber 20 which communicates with both, the annular chamber between the sleeve 18 and the jacket, and between the sleeve and the cylinder barrel. The coolant will flow from chamber 20 through spaces 29 in flange 28 upwardly into and outwardly in the annular chamber between the sleeve and the cylinder barrel in a rapid thin stream, through the spaces 33 in flange 32 on the

cylinder-barrel to the outer end of the annular chamber between the cylinder barrel and the sleeve, and then through ports 26 which extend through the sleeve 18 and annulus 8 into the arcuate channel 23 from which the coolant will flow to the pipe f. This flow of the coolant causes efficient cooling of the cylinder and a rapid flow through the annular space between the sleeve 18 and the cylinder barrel which will cause the barrel to be wiped free of air or gas bubbles while the engine is being used in different attitudes such as occurs when it is installed in aircraft.

The invention exemplifies means for cooling cylinders to and from which the coolant is conducted from the cylinder head which is also cooled. The invention also exemplifies cylinder-cooling means which comprises a sleeve and means for causing the coolant to flow in a thin rapid stream around the cylinder barrel and which causes the removal of air or gas bubbles in the coolant while the cylinder is in operation at different attitudes. The invention also exemplifies a cylinder and a jacket unit which can be assembled for installation with the cylinder-head which is provided with inlet and outlet connections for the coolant.

The invention is not to be understood as limited to the details described, since these may be modified within the scope of the appending claims without departing from the spirit and scope of the invention.

Having thus described the invention, what I claim as new and desire to secure by Letters Patent is:

1. Means for cooling an engine cylinder having its outer end secured in a cylinder-head provided with inlet and outlet connections for the coolant, comprising: a coolant jacket spaced from the cylinder; a sleeve dividing the space between the cylinder and the jacket into inner and outer annular chambers and terminating outwardly of the inner end of the jacket, for communication between said annular chambers; a coolant duct in the head communicatively connected to one of said connections; means in the jacket for conducting coolant between said duct and the outer end of the jacket, for communication between said annular chambers; a coolant duct in the head communicatively connected to one of said connections; means in the jacket for conducting coolant between said duct and the outer end and one side of the annular chamber between the sleeve and the jacket; a second coolant duct in the head, oppositely disposed to the first mentioned duct and communicatively connected to the other connection; and means extending through the sleeve and the jacket for conducting coolant between the opposite side portion of the outer end of the annular chamber between the cylinder and the sleeve and said second arcuate duct.

2. Means for cooling an engine cylinder having its outer end secured in a cylinder head provided with inlet and outlet connections for the coolant, comprising: a coolant jacket spaced from the cylinder; a sleeve dividing the space between the cylinder and the jacket into inner and outer annular chambers and terminating outwardly of the inner end of the jacket for communication between said annular chambers; an arcuate coolant channel in the head communicatively connected to one of said connections; a series of ports in the jacket for conducting coolant between said arcuate channel and one side-portion 75 of the end of the annular chamber between the

sleeve and the jacket; a second arcuate coolant channel, oppositely disposed to the first mentioned channel in the head, and ports extending through the sleeve and the jacket, for conducting coolant between the opposite side-portion of the outer end of the annular chamber between the cylinder and the sleeve and said second arcuate duct.

3. Means for cooling an engine cylinder having its outer end secured in a cylinder head provided with inlet and outlet connections comprising: a coolant jacket spaced from the cylinder; a sleeve dividing the space between the cylinder and the jacket into inner and outer annular chambers and terminating outwardly of the inner end of the jacket for communication between said annular chambers; a coolant duct in the head communicatively connected to one of said connections; means in the jacket for conducting coolant between said duct and the outer end and one side of the annular chamber between the sleeve and the jacket; a second coolant duct in the head, oppositely disposed to the first mentioned duct and communicatively connected to the other connection; means extending through the sleeve and the jacket for conducting coolant between the opposite side portion of the outer end of the annular chamber between the cylinder and the sleeve and said second arcuate duct, and means in the annular chamber between the cylinder and the sleeve for dividing the flow of coolant therethrough.

4. Means for cooling an engine cylinder, comprising: a coolant jacket around and spaced from the cylinder; a sleeve dividing the space between the cylinder and the jacket into inner and outer annular chambers and terminating outwardly of the inner end of the jacket for communication between said annular chambers; means in the jacket for conducting the coolant between the outside of the jacket and a side portion of the outer end of the annular chamber between the jacket and the sleeve; and means extending through the opposite side portion of the outer end of the sleeve and the jacket for conducting coolant between the annular chamber between the cylinder and the sleeve and the outside of the jacket.

5. Means for cooling an engine cylinder, comprising: a coolant jacket around and spaced from the cylinder; a sleeve dividing the space between the cylinder and the jacket into inner and outer annular chambers and terminating outwardly of the inner end of the jacket for communication between said annular chambers; means in the jacket for conducting the coolant between the outside of the jacket and a side portion of the outer end of the annular chamber between the jacket and the sleeve; means extending through the opposite side portion of the outer end of the sleeve and the jacket for conducting coolant between the annular chamber between the cylinder and the sleeve and the outside of the jacket, and means in the chamber between the cylinder and sleeve for restricting the flow of coolant therethrough.

6. The combination with a cylinder-head provided with a chamber for circulating coolant therethrough and with inlet and outlet connections for the coolant and a cylinder having its outer end secured in said head of: a coolant jacket around and spaced from the cylinder; a sleeve dividing the space between the cylinder and the jacket into inner and outer annular chambers and terminating outwardly of the inner

end of the jacket for the flow of coolant between said annular chambers; an arcuate duct in the head communicating with one of the coolant connections; a series of ports in the jacket for conducting the coolant between said arcuate duct and one side portion of the outer end of the annular chamber between the jacket and the sleeve; a second arcuate duct in the head communicatively connected with the other coolant connection on the head; and a series of ports extending through the opposite side-portion of the outer end portion of the sleeve and jacket for conducting coolant between said second arcuate duct and the annular chamber between the cylinder and the sleeve.

7. The combination with a cylinder head provided with a chamber for circulating coolant therethrough and inlet and outlet connections for the coolant and a cylinder having its outer end secured in said head; of a coolant jacket around and spaced from the cylinder and having its outer end fitting around the cylinder and in the head; a sleeve having its outer end fitting around the cylinder and dividing the space between the cylinder and the jacket into inner and outer annular chambers and terminating outwardly of the inner end of the jacket for the flow of coolant between said annular chambers; an arcuate duct in the head around the sleeve and communicating with one of the coolant connections; a series of ports in the jacket and adjacent its outer end for conducting the coolant between said duct and one side-portion of the outer end of the annular chamber between the jacket and the sleeve; a second arcuate duct in the head around the sleeve and communicatively connected with the outer coolant connection on the head and a series of ports extending through the opposite side-portion of the outer end portion of the sleeve and jacket for conducting coolant between said second arcuate duct and the annular chamber between the cylinder and the sleeve.

8. Means for cooling an engine-cylinder comprising a coolant jacket having its ends fitting around the cylinder and spaced from the cylinder intermediate its ends; a sleeve having its outer end fitting between the jacket and the cylinder and dividing a portion of the space between the cylinder and the jacket into inner and outer annular chambers terminating outwardly of the inner end of the jacket for communication between said annular chambers; ports in the jacket for conducting coolant between the outside of the outer end of the jacket and a side portion of the outer end of the annular chamber between the jacket and the sleeve; a flange on the cylinder and between the cylinder and the inner end of the sleeve provided with passages for conducting coolant to the chamber between the annular sleeve and the cylinder; and ports extending through the sleeve and the jacket on the opposite side portion of the cylinder for the flow of coolant between the outside of the jacket and the chamber between the cylinder and the sleeve.

9. Means for cooling an engine cylinder comprising a coolant jacket having its ends fitting around the cylinder and spaced from the cylinder intermediate its ends, a sleeve having its outer end fitting between the jacket and the cylinder and dividing a portion of the space between the cylinder and the jacket into inner and outer annular chambers terminating outwardly of the inner end of the jacket for communication between said annular chambers; ports in the jacket for conducting coolant between the outside of the jacket and the chamber between the cylinder and the sleeve.

7

outer end of the jacket and a side portion of the outer end of the annular chamber between the jacket and the sleeve; a flange on the cylinder and between the cylinder and the inner end of the sleeve provided with passages for conducting coolant to the chamber between the annular sleeve and the cylinder; a flange adjacent on the cylinder, provided with passages for the coolant in the annular chamber between the cylinder and the sleeve; and ports extending through the sleeve and the jacket on the opposite side-portion of the cylinder for the flow of coolant between the outside of the jacket and the chamber between the cylinder and the sleeve.

10. Means for cooling an engine cylinder comprising a coolant jacket having its ends fitting around the cylinder and spaced from the cylinder intermediate its ends; a sleeve having its outer end fitting around the cylinder and dividing a portion of the space between the cylinder and the jacket into inner and outer annular chambers and terminating outwardly of the inner end of the jacket for communication between said annular chambers; an arcuate series of ports in the jacket for conducting coolant between the outside of the outer end of the jacket and a side portion of the outer end of the annular chamber between the jacket and the sleeve; interrupted means between the inner end of the sleeve and the jacket for spacing the inner end of the jacket and cylinder; a flange on the cylinder and between the cylinder and the inner end of the sleeve provided with passages for conducting coolant to the chamber between the annular sleeve and the cylinder; a flange adjacent on the cylinder, provided with passages for the coolant in the annular chamber between the cylinder and the sleeve; and an arcuate series of ports extending through the sleeve and the jacket on the opposite side portion of the cylinder for the flow of coolant between the outside of the jacket and the chamber between the cylinder and the sleeve.

11. Means for cooling an engine-cylinder and a cylinder-head having its outer end fitting in the head, comprising: a coolant jacket having its ends fitting around the cylinder, spaced from the cylinder intermediate its ends and its outer end fitting in the cylinder head; a sleeve within the jacket having its outer end fitting around the cylinder and dividing a portion of the space between the cylinder and the jacket into inner and outer annular chambers and terminating outwardly of the inner end of the jacket for communication between said annular chambers; channels in the head and extending around diametrically opposite portions of the jacket connections in the head for coolant and communicatively connected to said channels, respectively; ports in the jackets for conducting coolant between one of the channels and a side-portion of the outer end of the annular chamber between the jacket and the sleeve; and ports communicating with the other channel extending through the sleeve and the jacket on the opposite side-portion of the jacket, for the flow of coolant between the other arcuate channel and the chamber between the cylinder and the sleeve.

12. Means for cooling an engine cylinder and a cylinder head having its outer end fitting in the head comprising: a coolant jacket having its ends fitting around the cylinder, spaced from the cylinder intermediate its ends and its outer end fitting in the cylinder head; a sleeve within the jacket having its outer end fitting around the

8

cylinder and dividing a portion of the space between the cylinder and the jacket into inner and outer annular chambers and terminating outwardly of the inner end of the jacket for communication between said annular chambers; arcuate channels in the head and extending around diametrically opposite portions of the jacket connections in the head for coolant and communicatively connected to said channels, respectively; an arcuate series of ports in the jackets for conducting coolant between one of the arcuate channels and a side portion of the outer end of the annular chamber between the jacket and the sleeve; and an arcuate series of ports communicating with the other arcuate channel extending through the sleeve and the jacket on the opposite side portion of the jacket for the flow of coolant between the other arcuate channel and the chamber between the cylinder and the sleeve.

13. Means for cooling an engine cylinder having its outer end secured in a cylinder-head provided with inlet and outlet connections for coolant, comprising: a coolant jacket spaced from the cylinder and having its outer end fitting in the head and around the cylinder; a sleeve dividing the space between the cylinder of the jacket into inner and outer annular chambers and terminating outwardly of the inner end of the jacket for communicatively connecting said annular chambers; a pair of separated coolant ducts in the head and extending around and communicating with diametrically opposite side-portions adjacent the outer ends of the jacket; means in the jacket adjacent its outer end for conducting coolant between one of the arcuate ducts and one side-portion of the annular chamber between the sleeve and the jacket; and means extending through the jacket and sleeve for conducting coolant between the other oppositely disposed arcuate duct and the inner annular chamber, and whereby coolant will be successively circulated from one arcuate channel at one side of the head longitudinally through one of the annular chambers, and then longitudinally through the other annular chamber to the other arcuate duct in the head.

14. Means for cooling an engine cylinder having its outer end secured in a cylinder-head provided with inlet and outlet connections for coolant, comprising: a coolant jacket spaced from the cylinder having its outer end fitting in the head and around the cylinder; a sleeve dividing the space between the cylinder of the jacket into inner and outer annular chambers and terminating outwardly of the inner end of the jacket for communicatively connecting said annular chambers; a pair of arcuate coolant ducts in the head, communicatively connected to said inlet and outlet connections respectively, and extending around and communicating with diametrically opposite side-portions of the jacket respectively; a series of ports in the jacket adjacent its outer end for conducting coolant between one of the arcuate ducts and one side-portion of the annular chamber between the sleeve and the jacket; and a series of ports extending through the jacket and sleeve for conducting coolant between the oppositely disposed arcuate duct and the inner annular chamber, and whereby successively circulating coolant from one arcuate channel in one side of the head longitudinally through one of the chambers and then longitudinally through the other annular chamber to the other arcuate duct in the head.
